PORTRABLE LOUNGE SEAT

David J. Petersen, 2219 N. Washington St. 98406, and Bruce S. Martin, 2224 N. Puget Sound 98405, both of Tacoma, Wash.

Filed Aug. 12, 1968, Ser. No. 13,096

Term of patent 14 years

Int. Cl. D6—01

U.S. Cl. D15—11

Fig. 4.

Fig. 5.

Fig. 6.

FIG. 1 is a perspective view of a portable lounge seat as viewed from above looking at the front right side when folded for use as an ottoman.

FIG. 2 is a perspective view of the portable lounge seat of FIG. 1 when unfolded and used as a lounge.

FIG. 3 is a side view of the portable lounge seat as shown in FIG. 2 in its lounge position, the opposite side being similar.

FIG. 4 is a rear elevation of the portable lounge seat, as shown in FIGS. 2 and 3 in its lounge position.

FIG. 5 is a bottom view of the portable lounge seat, as shown in FIG. 1 in its ottoman position.

FIG. 6 is a bottom view of the portable lounge seat, as shown in FIGS. 2 and 3 in its lounge position.

We claim:

The ornamental design for a portable lounge seat, as shown and described.
